UNITED STATES PATENT OFFICE.

WILLIAM F. WITTICH, OF ERIE, PENNSYLVANIA.

WHEEL MECHANISM.

1,333,650.

Specification of Letters Patent. Patented Mar. 16, 1920.

Application filed March 3, 1917. Serial No. 152,259.

To all whom it may concern:

Be it known that I, WILLIAM F. WITTICH, a citizen of the United States, residing at Erie, in the county of Erie and State of Pennsylvania, have invented new and useful improvements in Wheel Mechanisms, of which the following is a specification.

This invention relates to wheel mechanisms and consists in certain improvements 10 in the construction thereof as will be herein-after fully described and pointed out in the claims.

The invention is illustrated in the accompanying drawings as follows:—

15 Figure 1 shows a section on the line 1—1 in Fig. 2.

Fig. 2 a section on the line 2—2 in Fig. 1.

Fig. 3 a side elevation of one of the springs.

Fig. 4 an end elevation of the same spring.

20 Fig. 5 a side elevation of an alternative construction.

Fig. 6 an end elevation of the spring shown in Fig. 5.

1 marks the vehicle axle, 2 the steering knuckle mounted therein, 3 a steering arm on the steering knuckle, 4 a steering rod, 5 an axle extending from the steering knuckle, 6 a bearing ring surrounding the axle, 7 rollers between the axle and the ring 6 forming a roller bearing for the wheel, and 8 and 9 disk flanges at the ends of the ring 6. An intermediate or floating part 10 has the flanges 12 which overlap the flanges 8 and 9 and form a sliding connection therewith. 35 A flange 13 is mounted on the axle and engages the outer face of the flange 12 and a flange 14 is secured to the axle and engages the outer surface of the flange 11.

40 A bearing ring 15 is arranged within the hub or intermediate part 10 and a spring 16 is arranged between the ring 7 and the ring 15. Rollers 17 are arranged between the ring 15 and the peripheral surface of the annular pocket in the part 10. From this it 45 will be seen that the intermediate portion or hub 10 has a double roller bearing with relation to the axle and is free to yield radially through the action of the spring. Flanges 18 extend outwardly from the part 10 and a ring 19 is telescopically mounted 50 within the flanges 18. A spring 20 is arranged between the ring 19 and the outer surface of the part 10 so that the ring 19 may yield radially with relation to the part

10 but is held in place by the flanges 18. 55 Plates 21 are secured to the ring 19 and extend upwardly toward the periphery of the wheel. Plates 22 and 23 are bolted to the plates 21 by bolts 24. The plate 23 has an inclosing flange portion 23^a with a flanged 60 opening 25. A cap 26 is screwed onto the flange 25 and forms a closure for the outer side of the wheel.

The plate 22 has an inwardly extending portion to which is secured a driven gear 27. 65 An annular flange 28 extends inwardly from the gear and operates against the inner surface of the flanged disk 13 on the axle. A driving gear 29 meshes with the driven gear 27. The gear 29 is fixed on the shaft 30. 70 The shaft 30 is journaled in a bearing 31. The bearing 31 has a sliding and pivotal mounting so that the gear 29 may follow the gear 27. A pin 32 extends upwardly from the knuckle 2 and is concentric therewith. 75 A mounting 33 is telescopically arranged on the pin 32. The mounting is provided with a groove 33^a which engages an annular tongue or shoulder 34 carried by the gear 27. This tongue and groove connection carries 80 the mounting 33 with the gear 27 both in a radial direction and as the gear is swung.

A drive shaft 35 is connected with a drive rod 36 by a universal joint 38. The rod or link 36 may be provided, if desired, with 85 devices for permitting of an axial contraction and expansion. This construction permits of driving the wheel and also of the swinging of the wheel and of the springing of the periphery of the wheel.

90 It will be noted that the driving is delivered to the periphery part of the wheel and consequently there is no driving through the springs nor any driving connection interfering with the free yielding action of 95 the wheel.

I prefer to form the springs 16 and 20 by providing the ring 39 of spring material and to strike up the lips 40 alternately having the connecting portion run circumferentially of the ring. This gives a very simple and yet very efficient ring in that the connecting portion is subjected to more or less torsion and the axially divided parts between the lips are subjected to actual flexure. 100

105 As an alternative construction I have shown in Figs. 5 and 6 a ring 41 in which the springs are struck up with the connect-

ing portion extending axially across the ring, the lips being bent over upon themselves.

What I claim as new is:—

- 5 1. In a wheel mechanism, the combination of a peripheral part, an inner part and a spring ring between said parts having spring projections struck up from the ring.

2. In a wheel mechanism, the combination of a peripheral part, an inner part and a 10 spring ring between said parts having spring projections struck up from alternate sides of the ring.

In testimony whereof I have hereunto set my hand.

WILLIAM F. WITTICH.
